TUNER

Bertram A. Schwarz and Ludwig J. Fichter, Kokomo, Ind., assignors to General Motors Corporation, Detroit, Mich., a corporation of Delaware

Application February 4, 1942, Serial No. 429,442

8 Claims. (Cl. 74—10)

This invention relates to indexing means and more specifically to indexing means associated with tuning apparatus for radio receivers. It has become quite common to construct radio receivers wherein by merely pressing upon either a pivoted or slidable member and actuating it over a short distance it is possible to tune a radio receiver to certain predetermined set stations in addition to the usual manual tuning knob. There are always a few radio stations to which the owner of a receiver ordinarily listens. These are of course generally the transmitters within a rather limited radius of the location in which the receiver is operated and these may be set up on automatic tuning apparatus.

It is therefore an object of our invention to provide actuatable means for automatically indexing the tuning mechanism of a radio receiver.

It is a further object of our invention to provide mechanism which may be easily reset to other stations as desired.

It is a still further object of our invention to provide tuning means which is rugged and dependable and will not jar off station.

With these and other objects in view, which will become apparent as the specification proceeds, our invention will be best understood by reference to the following specification and claims and the illustrations in the accompanying drawings, in which:

Figure 1 is a front elevation of a tuning mechanism according to our invention;

Figure 2 is an enlarged sectional view taken on line 2—2 of Figure 1;

Figure 3 is a top plan view of the tuner of our invention;

Figure 4 is an end elevation of our invention;

Figure 5 is a sectional view taken on line 5—5 of Figure 6;

Figure 6 is an enlarged sectional view taken on line 6—6 of Figure 4; and

Figure 7 is a sectional view taken on line 7—7 of Figure 3.

Referring now more specifically to the drawings, there is shown in Figure 1 the front plate 2 of a tuning mechanism through which project a volume control member 4 and a manual tuning knob 6 at the left and right hand extremities respectively and between which project a number of horizontally slidable push buttons 8 for so-called automatic tuning. The tuning mechanism is supported in a casing 10 which is in the form of a rectangular shallow box having two side plates 12 and 14. Supported between these side plates is a treadle bar assembly com-

posed of two horizontal rods 16 and 18 which are secured at their ends to plates 20 and 22. Plate 20 carries a substantially cylindrical boss 24 having a central depression within which is carried a small ball bearing pivot 26 whose position is adjustable by a threaded member 28 in which it is carried which is supported on the side plate 12 and locked in position by a lock nut 30. The opposite plate 22 has secured rigidly thereto a short shaft 32 which extends through the side plate 14 and carries means thereon which may be manually operated to turn the treadle assembly and will later be described.

The outer end of both plates 20 and 22 has pivoted thereto a lever arm 34 and 36 respectively, the outer ends of each being pivotally connected to a transverse rod 38. This rod has a length greater than the distance between the two side plates 12 and 14 and the opposite ends extend through longitudinal slots 40 so that this rod may be slid longitudinally of the frame. Thus as the treadle bar rotates, the levers 34—36 cause the rod 38 to be moved longitudinally of the frame. Pivotally secured to the rod 38 at various axial points are a plurality of lugs 42 to which are threaded attached, in this instance comminuted core members 44, which cooperate with associated coils not shown per se which are located within shield cans 47. Thus, as the rod 38 moves, it in turn causes the tuning means, in this instance and for illustrative purposes only the comminuted cores, to tune the radio receiver.

The mechanism for adjusting the treadle bar assembly to various set positions will now be described and comprises a series of longitudinally extending shafts 46 which have the inner end extending through an opening 48 in a vertical portion 50 of the casing 10. The forward portion of each is carried by a second vertical portion 52. An intermediate portion of the shaft 46 carries a plurality of threaded portions 54 and 58 which are adjacent each other and are threaded in opposite directions. Adjacent the inner end of the threads 58 there is mounted a washer 60 which acts as a stop for one end of a helical spring 62 mounted on the rods, the opposite end of which bears against the inner surface of the vertical portion 50 of the frame. This tends to maintain a bias outwardly on each of the shafts 46.

The outer end of the threads 54 bears against a washer 64 which in turn bears against a plate 66 of sound insulating material on the inner surface of the member 52 to thus cause a stop in

the forward direction and also to absorb the noise when the plunger is forced forwardly. On the forward end of the shaft which extends through the front of the casing there is carried a long cylindrical member 68 having a portion larger in diameter adjacent the casing and is spring clipped to the shaft by a circular spring 70 which snaps into a notch 72 and which has an inwardly projecting tip 74 thereon which is adapted to slide over a flattened section 76 of the shaft to prevent the cylindrical member from rotating on the shaft. The outer end of the cylindrical member is knurled as at 78 and over this outer end there is adapted to be slid a hollow manual push button knob 8 which is maintained thereon by friction and also by some spring pressure from the locking spring 70.

Carried on the threaded portion 54 of the shaft is a traveling nut 82 which extends on both sides of the shaft and has secured thereto one end of a pin 84. It also has an opening 86 therein to slidably support the end of a second pin member 86'. Supported on the other threaded portion 58 is a second traveling nut 90 which slidably supports the opposite end of the pin 84 and rigidly supports an intermediate portion of the pin 86'. Each of these traveling nut assemblies has a projection 92 which extends down into a slot 94 in the bottom of the casing whereby these traveling nuts are prevented from rotating on the shaft but may move axially therealong.

The pins 84 and 86' are so located as to lie in alignment with the treadle bars 16 and 18, the axis of the shaft 46 passing between the two treadle bars. It will thus be evident that as the shaft 46 is rotated about its own axis, the traveling nuts will move either toward or away from each other, depending upon the direction of rotation, and that in so doing the pins 84 and 86' will move with respect to each other so that they are either in alignment or one or the other is ahead and thus when the shafts 46 are depressed by manual force applied to the end of the knob 8, they will set the treadle bar in a position dependent upon the position of the ends of the pins. This will in turn of course set the tuning mechanism to a similar position. Once the pins have been adjusted to the desired position, however, each reciprocal operation of a given knob 8 will always bring the treadle bar and tuning mechanism back to the same relative position and thus provide automatic tuning to the same radio transmitting station. In the device shown, five stations may thus be set up, though any number may be provided. It is of course necessary to provide also a manual means for setting the receiver at any intermediate point between the two limits of operation and in this case this is provided by a rotatable shaft 96 which is driven by the manual knob 6 and drives through a flexible cable 98 a worm wheel 100. This worm wheel 100 meshes with a gear 102 mounted on a collar 104 loosely mounted on the stub shaft 32. This worm drive is irreversible and must be disconnected when the automatic buttons are depressed and therefore the collar and gear carry a clutch portion 106 which is adapted to engage a friction disc 108 which is rigidly connected to the shaft 32 by a set screw 110.

The collar 104 has in its outer surface a groove 112 in which lies a portion of a lever 114 which is pivoted to the frame at 116. A compression spring 118 bears against the frame and one end of the collar 104 and tends to force it axially to maintain the clutch parts in engagement. The

spring may be overcome however by movement of the lever 114 which pulls the clutch parts away from each other and disengages the clutch. The outer end of the lever 114 is connected to one end of an L-shaped lever 116' by a resilient connection such as 117, the main portion of the lever 116' lying parallel to the rear member 50 of the casing. It is mounted by means of short studs 118' which extend through slots 120 in its surface, thus providing means whereby it may slide transversely of the casing or parallel to the axis of the treadle bars.

There are in the surface of this lever a plurality of angularly upturned portions 122 which overlie the ends of the reciprocating shafts 46 which are drawn to a conical tip such as 124', thus forming a camming surface whereby with inward reciprocation of the shafts 46, the tip of the shaft 124' cams its associated projection 122 to cause the lever 116' to move toward the left of the tuning mechanism looking at the same from the front, thus moving the lever 114 to the left about its pivot and disengaging the clutch so that the treadle bar assembly and shaft 32 may move without any engagement with the irreversible worm and gear assembly of the manual drive when the automatic buttons are depressed.

In order, however, to set up new stations for the push buttons which are normally operated to bring in commonly used stations, it is necessary to provide a locking-in means so that the shaft 46 which is being reset to a new position of index may be locked in during the period that the operator wishes to rotate the shaft for this purpose and he will not have to hold in and turn at the same time. Normally, of course, upon merely depressing the shaft as soon as the two pins 84 and 86' have forced the treadle bar around to a bottoming position, the shaft 46 is immediately returned to its outer inoperative position by the coil spring 62. However, for resetting purposes we provide a transverse latch bar 124 which extends across the front of the frame and lies just within the front panel. This bar is roughly of U-shape and is pivoted at its extremities 126 in the side plates 12 and 14 of the frame. It has a rear section which is stamped upwardly, as best shown in Figure 2, to form a raised portion 128 and the forward portion thereof is tapered upwardly as shown at 130 so that when any one of the push buttons is depressed, the transverse bar 124 is lifted due to the camming action of the surface 130 with the enlarged portion of the member 68 on the shaft 46. As the portion proceeds to the rear, however, it passes under the bar 124. If the manual knob 8 is in place, no locking action occurs as the upper surface of 8 merely holds the locking bar up and the shaft is forced back out as soon as manual pressure is removed, but when the manual knob 8 is removed, the part 68 will pass through under the bar and the front face of the enlarged portion of the member 68 at 132 rides back until the transverse bar 124 snaps down and locks this member 68, and of course the shaft 46, in its innermost position. The vertical bias on this latch bar is provided by two helical springs 134 which force the upper face of the lever downwardly and are biased against two lugs on the frame.

When the shaft 46 being reset is locked thus in its inner position, the same may be rotated and in so doing of course the traveling nuts 82 and 90 are moved back and forth on the shaft to adjust the pins 84 and 86' which are now in contact

with the treadle bar until the desired station is tuned in. The knob 8 is then reapplied to the end of the shaft and such application forces the locking plate 124 upwardly and releases this shaft again to its inoperative position. Thus one after another the various shafts may be adjusted to bring the tuning mechanism to any desired position. To tune the receiver to any other station than those set up on the push buttons, it is of course only necessary to manually rotate the manual knob 6 which is connected to the tuner at all times, except during actuation of one of the push buttons.

In order to prevent the tuning mechanism from drifting off station due to vibration, it will be obvious that when one of the automatic push buttons has been actuated to bring the device to a station, as soon as it is released the clutch member will again engage the manual drive and the irreversible worm gear will act as a locking means to maintain the tuning mechanism in its adjusted position.

We claim:

1. In tuning mechanism, means for tuning a radio receiver, pivoted means extending a substantial distance on each side of its axis connected to the tuning means to move the same, a plurality of spaced reciprocable and rotatable rods supported at right angles in at least one plane to the pivoted means, each having threaded portions of opposite sign, blocks threaded on each of the portions, means to prevent the blocks from rotating, spaced abutments each of which is carried by both the blocks of each reciprocating rod which project toward and engage the pivoted means to turn the same upon reciprocation of the rod, whereby rotation of one of the rods causes relative motion between the abutments carried thereby for adjustment.

2. In tuning mechanism, means for tuning a radio receiver, means for moving said tuning means to a plurality of predetermined positions, a pivoted member for driving the moving means, a plurality of rotatable and reciprocable members movable at right angles to the axis of the pivoted member, adjustable members on each of the last mentioned members on opposite sides thereof and projecting toward the pivoted member adapted to engage and index the same whose position may be changed by rotation of the first named members, removably manually engageable means to actuate each of the plurality of members separately and independently mounted thereon, and locking means engageable with and adapted to maintain any one of the members movable at right angles at one extreme of their travel only when the manually engageable means is removed but simultaneously permit rotation for adjustment of the adjustable members.

3. In tuning mechanism, means for tuning a radio receiver, a pivoted member having substantial surface area on both sides of its axis of rotation, reciprocable and rotatable spaced rods mounted at right angles to the pivoted member in at least one plane having oppositely threaded portions, traveling nut assemblies on each threaded portion, abutments on each nut assembly projecting toward the pivoted member whereby as the rods are rotated the relative position of the abutments will be changed and index the pivoted members to a different position upon reciprocation of the rod, manual means for directly rotating the pivoted member, removable

5 manual knobs mounted on the extending end of each rod, and spring biased locking means engageable with said rods and operative only when the knob is removed to maintain the rod actuated in its innermost position.

4. In tuning mechanism, means for tuning a radio receiver, a pivoted member having substantial surface area on both sides of its axis of rotation, reciprocable and rotatable spaced rods mounted at right angles to the pivoted member having oppositely threaded portions, a pair of spaced traveling nuts on each rod whereby as the rod is rotated the nuts will move relatively, a pair of axially extending pins carried in both nuts on opposite sides of each rod, said pins being alternately secured to the nuts so that relative motion between the nuts will alter the vertical alignment of the pins, said pins extending toward and adapted to engage the pivoted member to index the tuning mechanism upon reciprocal movement of each rod and adjustable to different positions by rotation of each rod.

5. In tuning mechanism, means for tuning a radio receiver, a pivoted member having substantial surface area on both sides of its axis of rotation, reciprocable and rotatable spaced rods mounted at right angles to the pivoted member having oppositely threaded portions, a pair of spaced traveling nuts on each rod whereby as the rod is rotated the nuts will move relatively, a pair of axially extending pins carried in both nuts on opposite sides of each rod, said pins being alternately secured to the nuts so that relative motion between the nuts will alter the vertical alignment of the pins, said pins extending toward and adapted to engage the pivoted member to index the tuning mechanism upon reciprocal movement of each rod and adjustable to different positions by rotation of each rod, removable manually engageable means mounted on each rod end, and locking means to retain the rod in its innermost position when the manually engageable means is removed but inoperative to lock the rods when the manually engageable means is in position.

6. In tuning mechanism, means for tuning a radio receiver, a pivoted member having substantial surface area on both sides of its axis of rotation, reciprocable and rotatable spaced rods mounted at right angles to the pivoted member having oppositely threaded portions, a pair of spaced traveling nuts on each rod whereby as the rod is rotated the nuts will move relatively, a pair of axially extending pins carried in both nuts on opposite sides of each rod, said pins being alternately secured to the nuts so that relative motion between the nuts will alter the vertical alignment of the pins, said pins extending toward and adapted to engage the pivoted member to index the tuning mechanism upon reciprocal movement of each rod and adjustable to different positions by rotation of each rod, means for manually rotating the pivoted member, clutch means between the manual drive and the pivoted member and means actuated by the reciprocating movement of any rod to disengage the clutch means.

7. In tuning mechanism, means for tuning a radio receiver, a pivoted member having substantial surface area on both sides of its axis of rotation, reciprocable and rotatable spaced rods mounted at right angles to the pivoted member having oppositely threaded portions, a pair of spaced traveling nuts on each rod whereby as

the rod is rotated the nuts will move relatively, a pair of axially extending pins carried in both nuts on opposite sides of each rod, said pins being alternately secured to the nuts so that relative motion between the nuts will alter the vertical alignment of the pins, said pins extending toward and adapted to engage the pivoted member to index the tuning mechanism upon reciprocal movement of each rod and adjustable to different positions by rotation of each rod, removable manually engageable means mounted on each rod end, locking means to retain the rod in its innermost position when the manually engageable means is removed but inoperative to lock the rods when the manually engageable means is in position, means for manually rotating the pivoted member, clutch means between the manual drive and the pivoted member and means actuated by the reciprocating movement of any rod to disengage the clutch means.

15
20

8. In tuning mechanism, means for tuning a radio receiver, means for moving said tuning means to a plurality of predetermined positions, a plurality of reciprocable and rotatable members movable toward said second-named means, adjustable means threadedly mounted on the reciprocable means engageable with the means for moving the tuning means to cause it to tune the receiver when one of the members is reciprocated and to be adjustable to different stations when the latter is rotated, removable manually engageable means mounted on each reciprocable member, spring biased locking means engaging the reciprocable members but incapable of operation to lock them unless the manually engageable means has been removed.
